UNITED STATES PATENT OFFICE.

MARINER S. LAWRENCE, OF WAKEFIELD, MASSACHUSETTS.

URINAL.

1,228,452.

Specification of Letters Patent.

Patented June 5, 1917.

Application filed March 26, 1917. Serial No. 157,348.

To all whom it may concern:

Be it known that I, MARINER S. LAWRENCE, a citizen of the United States, residing at Wakefield, county of Middlesex, State 5 of Massachusetts, have invented an Improvement in Urinals, of which the following description, in connection with the accompanying drawing, is a specification, like characters on the drawing representing like parts.

10 This invention relates to urinals such as are worn by male persons who are afflicted with incontinence of urine and has for its object to provide an improved urinal which will receive the urine as it flows without 15 danger that the discharged urine will leak or run over the upper edge of the urinal even when the person wearing the same is sitting down.

In order to give an understanding of my 20 invention, I have illustrated in the drawings a selected embodiment thereof which will now be described, after which the novel features will be pointed out in the appended claims.

25 In the drawings Figure 1 shows a device embodying my invention;

Fig. 2 is a vertical central section through the device shown in Fig. 1;

30 Fig. 3 is a horizontal section on the line 3—3, Fig. 2.

The device illustrated comprises a pouch member 1 which is adapted to be strapped to the body of the wearer in such a position that the penis will be inclosed in the pouch.

35 The pouch is made wider at its upper end and is provided with the rearward extension 2 in which the testicles are received, and at its front end it is provided with the upwardly-directed apron 3 which overlies the 40 abdomen of the wearer. The device is also provided with the straps 4 by which it may be strapped in place.

Extending across the pouch at approximately the base of the extension 2 is a diaphragm or partition 5 which is provided with an opening 6 to receive the penis and depending from the diaphragm is a circular 45 apron 7.

The device as thus far described is of 50 known construction. In the use of a urinal of this type it sometimes happens that the urine will flow back into the extension 2 and leak over the upper edge of the extension, especially when the person wearing the 55 device is in a sitting posture. In order to overcome this difficulty and to provide a

urinal which will prevent any possible leakage of the urine at the rear, I propose to make the urinal with an additional guard diaphragm 8 which extends across the rear 60 extension 2 above the bottom thereof and thus forms a pocket 9 which will catch and retain any liquid which tends to flow backwardly toward the rear of the device. The provision of this guard diaphragm 8 prevents any possibility of liquid leaking over 65 the rear edge of the urinal. I will also preferably extend the guard diaphragm 8 clear to the front wall of the pouch in which case said diaphragm will be provided with an 70 opening 10 for the reception of the penis. By this construction added protection is afforded against any leakage of the liquid.

One source of annoyance in the use of a 75 urinal of this type arises from the fact that the penis sometimes becomes withdrawn from the opening 6, in which case the liquid will be discharged above the diaphragm 5 rather than into the pouch below said diaphragm. In order to avoid such an occurrence, I propose to make the opening 10 in the guard diaphragm 8 by forming therein a U-shaped slit and then turning up the flap 11 formed by the slit, the turning-up of the flap providing the necessary opening for the 80 penis. By making the slit so that the flap when turned up is on the front side of the opening, said flap will assist in retaining the penis in said opening. Urinals of this type are usually made of rubber and the natural 85 tendency of the flap 11 will be to swing down downwardly into a plane parallel with the diaphragm, and the flap will thus press against the penis and tend to hold it in position. Further, by this construction the 90 size of the opening 10 will automatically accommodate itself to the size of the penis so that there is less likelihood of any leakage 95 occurring.

12 is a receptacle which is adapted to be 100 detachably secured to the lower edge of the pouch 1 and which may be strapped to the leg of the user, all as usual in devices of this nature.

The diaphragm 8 also acts to support the 105 testicles so as to prevent them from coming in contact with any liquid which may accumulate in the pocket 9.

I claim:

1. A urinal comprising a pouch having an 110 open top shaped to fit the body of the wearer, a partition extending across said

pouch adjacent the top and provided with a penis-receiving aperture, said pouch having a rearward extension above said partition, and a guard diaphragm extending across 5 said rearward extension above the bottom thereof and forming therewith a pocket to retain any liquid which may be discharged over the top of said partition.

2. A urinal comprising a pouch having an 10 open top shaped to fit the body of the wearer, a partition extending across said pouch adjacent the top and provided with a penis-receiving aperture, said pouch having a rearward extension above said diaphragm, and a guard diaphragm extending 15 across the pouch above said partition, said

guard diaphragm being provided with a penis-receiving aperture.

3. A urinal comprising a pouch having an open top shaped to fit the body of the 20 wearer, a partition extending across said pouch adjacent the top and provided with a penis-receiving aperture, said pouch having a rearward extension above said diaphragm, and a guard diaphragm extending 25 across the pouch above said partition, said guard diaphragm being provided with a U-shaped slit through which the penis may be inserted.

In testimony whereof, I have signed my 30 name to this specification.

MARINER S. LAWRENCE.
